FEED DEVICE

Edward F. Harmon, Flushing, N. Y., assignor to
E. I. du Pont de Nemours & Company, Wil-
mington, Del., a corporation of Delaware

Original application December 13, 1935, Serial No.
54,301. Divided and this application January
24, 1938, Serial No. 186,620

6 Claims. (Cl. 198—26)

This is a division of my application for patent Serial No. 54,301, filed December 13, 1935, which has issued as Patent No. 2,135,751.

The principal objects of this invention are to provide for the feeding of a toothbrush or other brush with the bristles encased, if desired, in an envelope of cellulose, water-proof paper or the like, and to provide means for turning the brushes endwise during the feeding of the brushes into a machine and guiding them into the open tops of envelopes, or the like.

Other objects and advantages of the invention will appear hereinafter.

Reference is to be had to the accompanying drawings, in which

Fig. 1 is an elevation of the brush feeding-in mechanism, constructed in accordance with this invention;

Fig. 2 is a plan of a part of an auxiliary drive connected therewith;

Fig. 3 is an end view of the same, as indicated by the arrow 3 in Fig. 2;

Fig. 4 is a plan of the feeding-in chute for the brushes as indicated by the arrow 4 in Fig. 1;

Fig. 5 is a similar view of the brush tilting means, taken in the direction of the arrow 5 in Fig. 1;

Fig. 6 is a plan of the lower part of the stop for the brush, taken in the direction of the arrow 6 in Fig. 1;

Fig. 7 is an elevation looking in the direction of the arrow 7 in Fig. 1;

Fig. 8 is a plan showing the connection for driving, and

Fig. 9 is a sectional view on the line 9—9 of Fig. 8.

In order to feed brushes, especially toothbrushes, into the machine which is the subject matter of my original application, Serial No. 54,301, the power for operating the feed is obtained from the turret thereof, not shown herein. An auxiliary drive shaft of the turret drives through a bevel gear 120, and drives a shaft 121 on which is a disc 122 having a roll 123 and a second disc 124 having a generally cylindrical outline and constituting a part of a Geneva motion. The roll 123 enters radial notches 125 in a disc 126 on the shaft 127 of the turret. The circumference of the disc 124 engages concave surfaces 129^a on a wheel 129 also fixed to the shaft 127. This constitutes the remainder of the Geneva motion. The disc 124 has a notch 128 to permit the intermittent rotation of the wheel 129.

It will be seen that the constant rotation of the shaft 121 with its discs results in rotating the disc 126 and therefore the shaft 127 intermittently through a quadrant, in the form shown. Then the disc 124 holds the wheel 129 in the stationary position until the roll 123 runs into the next notch 125. At that time the wheel 129 is released and allowed to rotate by the shaft.

The brushes which are to be packaged or sealed are brought in by any ordinary endless conveyor 220 having projections 221 for engaging the bristles at the lower end and carrying the brushes up to a guide 222. This guide consists of two separated rails inclined in such a way that when the brush drops off the conveyor 220 over its upper guide wheel 223 they will fall into this guide and be carried down by gravity.

At a point along the guide the sliding motion of the brushes down the guide is interrupted by a pair of alternatingly moving stops 224. These stops reciprocate in one of the rails and across the guide. They are connected with an oscillating lever 225 which is operated by a slide 226. This slide reciprocates in a guide 227. On the shaft 121 is a trip cam 228 which forces forward the slide 226. After the cam has moved, a spring 230 restores it and its cam roll 231 to retracted position.

The slide 226 has a pin 232 entering a slotted reciprocating bracket 234 and moves with it a vertical rod 235 carried by said bracket. This rod 235 through universal joints 236, oscillates a shaft 237 which carries the lever 225. This reciprocates the two stops 224 alternately and stops each brush at this point. As each brush is released from these two stops it moves by gravity down to the position shown in Fig. 1, at which point the lower end of the handle of the brush enters a trough 240. This trough has a stopping surface 241 which prevents this end of the brush moving further. The brush swings down and falls off the end of the rails 222 and necessarily tips over into the position shown in dotted lines in Fig. 1.

The brush enters a guiding device 242 which has a front door 243 latched in position by a latch 244. In tipping over the brush hits a spring 245 to check its motion and enters between a pair of converging walls 246. At the bottom of this hopper formed by these walls is a vibrating stop 247 actuated by the rod 235 on which it is mounted. This stop is for the purpose of preventing more than one brush starting down into a brush chute together. This

directs the brushes into the machine described in my said original application.

Thus a toothbrush or other brush is fed up by the conveyor, hanging by gravity from the 5 bristle end, and reversed into the hopper which feeds it by gravity down into the machine with its handle end up.

Having thus described my invention and the 10 advantages thereof, I do not wish to be limited to the details herein disclosed, otherwise than as set forth in the claims, but what I claim is:

1. The combination with a pair of rails in inclined position, of means for introducing brushes with the handles depending between the 15 rails and the bristles supporting the brushes on the rails, a shaft, a cam on said shaft, a slide movable by the cam, a support, a rod extending upwardly from the support and oscillatable on its own axis, a pair of stops extending in between 20 the rails from the same side, and means connected with said rod for oscillating said stops alternately to stop the line of brushes down the rails and separate them.

2. The combination with a pair of rails in 25 inclined position, of means for introducing brushes with the handles depending between the rails and the bristles supporting the brushes on the rails, a shaft, a cam on said shaft, a slide movable by the cam, a support, a rod extending 30 upwardly from the support and oscillatable on its own axis, a pair of stops extending in between the rails, means connected with said rod for oscillating said stops alternately to stop the line of brushes down the rails and separate them, a 35 hopper in position for receiving the brushes from the rails, and an arm fixed to said rod to oscillate therewith and located at the bottom of the hopper, the parts being so located as to cause said arm to stop the brushes in their further advance and time them so that they will be discharged from the hopper in the proper order.

3. The combination with a pair of rails in inclined position, of means for introducing brushes

with the handles depending between the rails and the bristles supporting the brushes on the rails, a shaft, a cam on said shaft, a slide movable by the cam, a support, a rod extending upwardly from the support, said slide constituting 5 means for oscillating the rod on its vertical axis, a hopper into which the brushes are discharged from the rails, and an arm on said rod and oscillatable with it and arranged to move into the hopper to stop the brushes at definite intervals. 10

4. The combination with a pair of rails in inclined position, of means for introducing brushes with the handles depending between the rails and the bristles supporting the brushes on the rails, a rod extending upwardly, means for oscillating the rod on its vertical axis, a hopper into which the brushes are discharged from the rails, and an arm on said rod and oscillatable with it and arranged to move into the hopper to stop the brushes therein at definite intervals. 15 20

5. The combination with a pair of rails in inclined position for supporting brushes, a rod extending upwardly, a pair of stops extending in between the rails, means connected with said rod for oscillating said stops alternately to stop the 25 line of brushes down the rails and separate them, a hopper in position for receiving the brushes from the rails, and an arm fixed to said rod to oscillate therewith and located at the bottom of the 30 hopper to stop the brushes in their further advance and time them so that they will be discharged from the hopper in the proper order.

6. The combination with a pair of rails in inclined position, of means for introducing brushes with the handles depending between the rails and the bristles supporting the brushes on the rails, a vertical rod oscillatable on its own axis, a pair of stops extending in between the rails from the same side, and means connected with 35 said rod for oscillating said stops alternately to stop the line of brushes down the rails and separate them. 40
